SPINNING APPARATUS

Henry J. McDermott, Collingdale, Pa., assignor
to American Viscose Corporation, Wilmington,
Del., a corporation of Delaware

Application December 1, 1949, Serial No. 130,462

11 Claims. (Cl. 18—8)

1

This invention relates to equipment for producing filamentary material by discharging small streams of a spinning solution into a bath which converts the streams into filaments, and particularly to equipment adapted to produce viscose filaments.

It is customary to discharge viscose solution or other filament-forming liquids from a spinneret into a liquid coagulant which is maintained at a desired level above the spinneret and at a desired temperature. A single spinning machine may comprise fifty or more spinnerets which are submerged within a single spinning bath container; on other installations, a separate container may be provided for each spinneret.

In the spinning apparatus in use at present, a spinning solution is passed through members of an assembly (in the order named) comprising a filter, a rounder, and a spinneret. The assembly is pivotably supported by a portion of the filter case so that the spinneret may be swung into and out of the spin path. An adjustable stop limits the swinging of the assembly and determines the depth of spinneret immersion. The degree of immersion may be changed also by loosening the coupling which joins the rounder to the filter case and turning the rounder with respect to the coupling to raise or lower the spinneret with respect to the bath surface. The depth of immersion is measured by manually inserting a rule into the bath to each spinneret face. Coating of the stop surfaces with corrosion products, spinning solution decomposition products, or spinning bath materials may appreciably affect the depth of spinneret immersion. The equipment is therefore frequently inspected and these surfaces cleaned, if necessary. When spinning yarns at less than 100 meters per minute, depth settings of the spinnerets may be permitted to vary within a sixteenth of an inch over or under the specified setting. However, when spinning filaments at speeds greater than 150 meters per minute, liquid of the spin bath collects and is supported upon the filamentary material leaving the spinneret in substantial quantity. The amount of liquid carried by the filaments may be controlled by varying the depth of spinneret immersion. The depth of the bath and also the temperature thereof have marked effect on the dyeing and physical properties of the yarn and it becomes increasingly important, as the spinning speed is increased, to maintain the depth settings of the spinneret and the bath temperatures at substantially constant levels.

It is an important object of the invention to 55 bracket 8 as shown in Fig. 2 to engage an axial

2

provide apparatus which effects positive and accurate depth of spinneret immersion. It is another object to provide spinning equipment which permits economical use of a liquid coagulant applied to the material discharged from a spinneret. It is still another object to provide means for accurately controlling the temperature of a coagulant or other liquid used in producing filaments. Other objects, features and advantages of the invention will become apparent in the following description of the invention and the drawings relating thereto in which

Fig. 1 is an elevation partly in section of spinning equipment according to the invention;

15 Fig. 2 is a side view of an assembly comprising a portion of the apparatus illustrated in Fig. 1; and

Fig. 3 is a top view of the apparatus of Fig. 1.

According to the invention, a spinneret is supported within a small cup-shaped or open-topped container to maintain accurate immersion of the spinneret. The face of the spinneret is substantially horizontal at a depth below an overflow surface of the container corresponding to a desired immersion depth. The spinneret and container are preferably supported on a bracket which may be swung into and out of a vessel for receiving the liquid which overflows from the immersion container. The bracket is provided with a liquid-receiving recess and a duct connected therewith having a discharge orifice positioned to discharge liquid into the container. Liquid is supplied to the recess of the bracket by a stationary orifice which is connected with a supply of liquid and positioned to discharge liquid into the recess when the bracket occupies its spinning position; when the bracket is swung out of this position the liquid is discharged into the vessel in which the bracket is suspended.

40 Fig. 1 illustrates a bracket 5 having an end portion 6 in pivotable relationship with a bifurcate clamping bracket 8. The bracket 6 with parts attached thereto is swingable into and out of a vessel 10 on a pivotal axis extending through the bracket 8. Its position within the vessel is determined by engagement of a stop surface 11 (Fig. 2) of the bracket 5 with the surface 13 of the bracket 8 (Fig. 1).

The bracket 8 is connected with a supply source 50 of filament-forming material and is provided with a fitting 12 having a passageway 15 for introducing the material into a passageway of the bracket 5.

The fitting 12 extends through one leg of the bracket 8 as shown in Fig. 2 to engage an axial

recess 14 in the bracket 5. The bore 15 is contiguous with the passageways 16 and 17 of the bracket 5. Passageway 17 terminates within an enlarged portion 19 of the bracket 5 which is recessed and interiorly threaded to receive a coupling 20. The passageway 17 terminates at its other end in a threaded recess which receives a threaded plug 23 which may be removed for any purpose such as cleaning the passageway.

An extension member 26 (Fig. 1) is attached to an end portion 25 of the bracket 5 by such means as a cap screw 27. The member 26 is provided with a threaded recess to receive a male coupling 29 and an exteriorly threaded projection 30 which receives an immersion cup 32. A spinneret 34 is coupled to the member 26 by the cup 32. A passageway extends through the member 26 between the recess and the end surface of the projection 30. A coiled rounder 24 is attached to the bracket by couplings 20 and 29 to connect the passageways 17 and 36.

A recess 40 is provided in the side of the bracket and extends downwardly within the bracket to form a pocket 41. A passageway 42 extends from a wall of the pocket 41 to the side of the bracket to terminate in an orifice 43 facing the cup 32 to a position just above but slightly offset with respect to the outer periphery of the cup.

Liquid for treating the filament-forming material discharged by the spinneret is supplied to the above described spinning equipment through an orifice member 45 which may be attached on the edge of the container 10 by such means as the clamp arrangement shown wherein legs of a bifurcate portion of the member extend over the edge 41 of the container 10; a cap screw 48 extending through one of the legs may be tightened to secure the member to the container. Liquid passing from a supply source not shown enters the member from a tube 50 secured to a fitting 51 extending in threaded relationship through a wall of the member into a chamber 53. An orifice tube 55 is secured within the enlarged portion of the chamber by such means as a resilient stopper 56. So that a safety hazard is not created by liquid spouting from the member when the orifice tube is removed for any purpose such as for cleaning the member, the member 45 is preferably designed so that liquid enters the member in a direction which is not in alignment with the direction along which the liquid passes from the member.

In operation, liquid passes from the member 45 through the orifice tube 55 in a trajectory which terminates within the recess 40 of the bracket 5. The liquid then collects within the pocket 41 and flows through the passageway 42 into the cup 32 to submerge the spinneret 34. The liquid continuously overflows the rim 57 of the cup and drops into the container or vessel 10.

The liquid may be permitted to leave the container 10 at any desired level lower than the rim 57 of the cup. Generally, the liquid may be utilized as a medium for heating the coils 59 of the rounder 24 and the filament-forming liquid passing therethrough. Preferably, the liquid level in container 10 is such as to submerge the coils 59, and the member 26.

In order to maintain a desirable temperature in the container 10 for heating the rounder coils, it may be necessary to provide a flow of liquid from orifice 55 at a rate much greater than the amount required in the cup 32, in which case the passageway 42 is limited in size to permit only a portion of the liquid to flow into the cup 32, the rest of

the liquid from orifice 55 overflows pocket 41. In actual operation, it was found that 500 cubic centimeters per minute of liquid flowing into cup 32 was sufficient to avoid turbulence about the face of the jet and provide a desired temperature. An orifice 43 of proper size was selected to obtain the desired rate of liquid delivery into the cup. Liquid was passed through the orifice 55 at the rate of 1000 cubic centimeters per minute. The excess liquid was permitted to overflow the pocket 41 and fill the vessel 10 to a level established by an overflow tube 65.

Although many arrangements are possible for introducing the liquid into the cup, a preferable system has been hereinabove described. An important advantage of the arrangement shown is that the bracket 5 and the parts supported thereon may be swung out of the container 10 without disconnecting any of the apparatus for conducting the liquid coagulant. Moreover, the flow of liquid into the cup 32 is automatically terminated when the bracket and spinneret are moved out of the spinning position, and the liquid issuing from the orifice tube 55 drops downwardly into the container 10 and flows therefrom through the normal channels. Also, by this method, the temperature of the liquid in the container 10 is maintained for heating the rounder coils.

As an important advantage of the invention, the depth of the liquid in the cup 32 over the spinneret face may be controlled within an accuracy within 100th of an inch. The cup 32 has an annular shoulder 60 which seats on the upper surface of the spinneret flange 61. A washer 62 is normally provided between the spinneret flange and threaded projection 30 onto which the cup 32 is screwed. Since the spinnerets are very accurately built to standard dimensions and the cup 32 may be readily constructed with equal accuracy, the distance between the respective planes of the spinneret face and the rim 57 may be readily varied by constructing cups such as the cup 32 having different flange heights to give any desired immersion of the spinneret. The cups may be constructed from any material such as that normally used to make the couplings which are used to secure spinnerets to conventional equipment, e. g. hard rubber, or lead alloyed with a small amount of antimony.

While preferred embodiments of the invention have been shown and described, it is to be understood that changes and variations may be made without departing from the spirit and scope of the invention as defined in the appended claims.

55 I claim:

60 1. Spinning apparatus for artificial filaments comprising a small container having an open top and an overflow surface, an upwardly facing spinneret supported within the container at a level below the overflow surface, a receptacle, common means for supporting the container and the spinneret within the receptacle, and an overflow surface for the receptacle disposed at lower level than that of the overflow surface of the container, and orifice means supported adjacent the container for discharging a liquid thereinto.

65 2. Spinning apparatus for artificial filaments comprising a small container having an aperture through the top portion thereof and an overflow surface, an upwardly facing spinneret supported within the container at a level below the overflow surface, a receptacle, a movable bracket for supporting the container and the spinneret within the receptacle, an overflow surface of the receptacle disposed at a lower level than that of the

container, and orifice means supported adjacent the container for discharging a liquid thereinto while the bracket is in the spinning position.

3. Spinning apparatus for artificial filaments comprising a small container having an open top and an overflow surface, an upwardly facing spinneret supported within the container at a level below the overflow surface, a receptacle, a movable bracket for supporting the container and the spinneret within the receptacle, an overflow surface for the receptacle disposed at a lower level than that of the container, orifice means supported by the bracket adjacent the container for discharging a liquid thereinto, a reservoir within the bracket for supplying a liquid to the orifice, said reservoir having an opening along an upper portion, and a second orifice means supported adjacent the bracket for discharging liquid into the reservoir through said opening.

4. Spinning apparatus for artificial filaments comprising a pivotably supported bracket, a spinneret supported on a portion of the bracket spaced from its pivot axis so that when the bracket is in its spinning position the face of the spinneret is substantially horizontal, a passageway extending through the bracket from a surface thereof within a pivot joint intersected by the pivot axis, means for supplying a filament-forming liquid to the passageway through the pivot joint, a second passageway extending through the portion of the bracket supporting the spinneret and connected therewith, a rounder connecting the two passageways, a coupling for securing the spinneret to the bracket having a flange which surrounds the spinneret and extends to a predetermined level above the spinneret, and means for introducing a liquid into the region enclosed by the flange.

5. Spinning apparatus as in claim 4 wherein the bracket is provided with a catch basin, said basin being positioned above the flange, and a passageway extending from the interior of the basin to a region above and closely adjacent the flange, and a stationary orifice connected with a liquid reservoir for directing a liquid into the basin when the bracket is in its spinning position.

6. Spinning apparatus as in claim 4 wherein the bracket is provided with a recess in the side opposite the spinneret and the coupling, said recess leading into a catch basin formed within the bracket, a duct leading from the lower portion of the basin to a region above and slightly offset with respect to the flange, and a stationary orifice connected to a liquid supply means spaced laterally from the recess when the bracket is in its spinning position to discharge liquid into the recess.

7. Spinning apparatus as in claim 6 wherein apparatus connecting the liquid supply means and the orifice comprises a fixture having an inner chamber, an inlet duct connected with the chamber, a supply line connected with the duct, an outlet port, an orifice tube for discharging the liquid from the chamber into the recess, and a quickly removable plug through which the orifice tube extends, said plug extending into the outlet port.

8. Spinning apparatus for artificial filaments comprising a small container having an open top and an overflow means, an upwardly-facing spinneret supported within the container at a level below the overflow means, a receptacle, common means for supporting the container and the spinneret within the receptacle, an overflow means for the receptacle disposed at a lower level than

that of the overflow means of the container, and means adjacent the container for discharging a liquid thereinto.

9. Spinning apparatus for artificial filaments comprising a small container having an open top and a peripheral overflow surface, an upwardly-facing spinneret supported within the container at a level below the overflow surface, common means for supporting the container and the spinneret, duct means for supplying a filament-forming liquid to the spinneret, said duct means extending through at least a portion of the support means and a portion of the container into communication with the spinneret, a receptacle disposed exteriorly of the container and having a liquid-receiving region disposed at a lower level than that of the overflow surface of the container to catch liquid passing from the overflow surface, and means adjacent the container for discharging a liquid thereinto.

10. Spinning apparatus for artificial filaments comprising a movable bracket, stop means for holding the bracket in a position for spinning, a small container having an open top and a peripheral overflow surface, an upwardly-facing spinneret supported within the container at a predetermined level below the overflow surface, said container and spinneret being mounted on the bracket, duct means for supplying a filament-forming liquid to the spinneret, said duct means extending through at least a portion of the bracket and a lower portion of the container into communication with the spinneret, a receptacle disposed exteriorly of the container and having a liquid-receiving region disposed at a lower level than that of the overflow surface of the container for the purpose of catching liquid passing from the overflow surface, and means adjacent the container for discharging liquid thereinto when the bracket is in the position wherein it engages the stop means.

11. Spinning apparatus for artificial filaments comprising a pivotably supported bracket, stop means for holding the bracket in a position for spinning, a spinneret, coupling means having an upwardly-extending flange for securing the spinneret to a portion of the bracket remotely spaced from its pivot axis, the face of the spinneret being substantially horizontal and said flange extending above the spinneret face to a predetermined level to form a liquid storage region surrounding the spinneret when the bracket rests against the stop means, a receptacle having a liquid receiving region disposed at a lower level than that of the upper portion of the flange to receive liquid therefrom, and means positioned for introducing a liquid into the region enclosed by the flange when the bracket rests against the stop means.
